UNITED STATES PATENT OFFICE.

HERBERT F. PROVANDIE, OF MELROSE, MASSACHUSETTS, ASSIGNOR TO AMERICAN WATER SUPPLY COMPANY OF NEW ENGLAND, OF BOSTON, MASSACHUSETTS, A CORPORATION OF MASSACHUSETTS.

MACHINE FOR FORMING PAPER RECEPACLES.

1,107,225.

Specification of Letters Patent.

Patented Aug. 11, 1914.

Application filed August 30, 1913. Serial No. 787,430.

To all whom it may concern:

Be it known that I, HERBERT F. PROVANDIE, a citizen of the United States, residing at Melrose, in the county of Middlesex and 5 State of Massachusetts, have invented an Improvement in Machines for Forming Paper Receptacles, of which the following is a specification.

Certain kinds of paper receptacles are 10 composed of frusto-conical bodies and bottom-pieces having notched edges bent to form a flange, which flange is adapted to extend over the outside, or it may be the inside of the lower ends of the body, and to be 15 secured thereto by paste or other adhesive material which is herein termed "paste."

This invention has for its object the construction of a machine for securing the flanged bottom-pieces to the bodies and consists in the combination of a form of a shape 20 corresponding to the shape of the completed paper receptacle upon which the body is placed, and also the bottom-piece, and a pressure-device, made as an inverted cup or 25 otherwise formed coextensive with the bottom-piece, adapted to be moved into engagement with the bottom-piece on the form to press its flange into firm engagement with the end-portion of the body, and means to 30 support said pressure-device to admit of its being moved toward and from the form, said supporting-means having associated with it means to hold it in both its engaging and disengaged positions. Automatic means 35 are or may be provided for moving the pressure-device out of coöperative relation with the form to disengage and permit removal of the receptacle from the form, and said automatic means may be so constructed 40 as to admit of manual movement of the pressure-device into coöperative relation with the form to engage the bottom-piece. The machine also embodies means for heating the paper receptacle while it is held by 45 the pressure-device, thereby to dry and cause the adhesive material to set.

The machine involves a turret and a plurality of forms thereon, each form having associated with it a pressure-device and supporting-means therefor, but in such case the heating of the paper-receptacles will be done at a certain part of the cycle of operation of the turret, hence heating-means are provided only at a certain place, which is so ar- 50 ranged that as the turret rotates the forms 55 with the receptacles thereon will be brought successively into position to become heated.

Figure 1 is a plan view of a machine for forming paper receptacles embodying this invention. Fig. 2 is a vertical section of the 60 machine shown in Fig. 1, taken on the dotted line 2—2. Fig. 3 is an enlarged side elevation of one of the forms with the component parts of a paper receptacle thereon, its pressure-device and supporting-means therefor; 65 the holding-means for the supporting-means and automatic means to move said supporting-means. Fig. 4 is a detail view of the automatic moving-means for the supporting-means. Fig. 5 is a rear elevation of one of 70 the forms and parts associated therewith. Fig. 6 is a side elevation of a completed receptacle, such as may be found on this machine embodying this invention.

10 represents the turret on which a plurality of forms are erected, which is made as a table. Said turret is secured to a sleeve 12 rotatably mounted on a stationary spindle 13, which is suitably supported. Said sleeve has secured to it a bevel-gear 15, which 80 is engaged by a bevel-gear 16, secured to a power-driven shaft 17. The turret is or may be continuously rotated by said power-driven shaft. The forms which are erected on the turret and upon which the paper receptacles 85 are formed are made of a shape corresponding to the shape of the receptacles to be formed. As the paper receptacles here shown, see Fig. 6, is of frusto-conical shape a frusto-conical form is represented at 20. 90 Said forms are here shown as stationarily supported on the turret by any suitable means, so far as this invention is concerned. The body 60 of the receptacle, which has been previously constructed and also provided with a line of paste around the outside of its small end-portion, is placed on the form, and then the bottom-piece, having a notched or other form of flange and which has been previously made, is placed on the 100 form on top of the body, although it will be obvious that their positions with respect to each other may be reversed. Then, it is herein designed and intended that pressure shall be applied to the bottom-piece and particularly to the flange thereof to firmly press it into engagement with the body and hold it while the adhesive material dries or sets. 105

As a pressure-device an inverted cup 25, is here shown, of suitable size and shape to fit upon the top of the form, and said cup has an ear 26, centrally disposed upon it, 5 which is loosely connected at 27 to one arm 28 of an angularly formed lever, the other arm 29 of which is pivoted at 30 to a stand 31 on the turret, thereby supporting the cup above the form and permitting it to be 10 moved up and down or into and out of engagement with a bottom-piece on the form. In order that the cup 25 may bear upon the bottom-piece with substantially an equal pressure over all, the supporting-arm 28 15 has at its extremity a projection 35 arranged to engage the cup at one side of the center and exert downward pressure thereupon when the supporting-arm is depressed to move the cup into engagement with the bottom-piece, and a strong leaf spring 36 is secured to the supporting-arm which bears upon the cup at the opposite side of the center.

The holding springs 40, one or more, as 25 may be required, are connected at their upper ends to the supporting-arm and at their lower ends to a stand 31, said springs extending across the pivot 30, and acting at one or the other side of said pivot according to the position of the arm. Thus when the supporting-arm is lifted said spring or springs will pass the pivot and act to assist in lifting the arm, and also to hold it in elevated position, and when the 35 arm is depressed said springs will pass the pivot 30 in a direction opposite to that heretofore described, and will act to depress the arm and also to hold it depressed. The degree of pressure which is applied to the 40 bottom-piece may be determined by the strength of said springs.

After the operator has placed a body and a bottom-piece on the form she moves the supporting-arm by hand to depress the pressure-device or cup, whereupon the springs 45 act to assist such movement, and thereafter hold the cup in firm engagement with the bottom-piece until said supporting-arm is moved in the other direction by automatic 50 means, provided for the purpose. As here shown said automatic means consists of a stationarily supported cam 45 arranged on the machine-frame, which is adapted to be engaged by an inclined yielding finger 46 55 on the supporting-arm, as represented in Figs. 3 and 4, which acts to move the arm on its pivot 30 and lift the pressure-device.

As the turret rotates continuously it will be observed that the operator may sit at 60 one side of the machine, as at X, for instance, and may remove the completed paper receptacle from the form and place upon the form a new body and bottom-piece, and then depress the supporting-arm by hand 65 and the movement of the turret is sufficiently

slow to enable the operator to perform these acts while the form passes in front of her. It is desirable to heat the paper receptacles to dry the adhesive material and better cause it to set, and, as here shown, one or 70 more gas-burners 50, may be arranged beneath the turret at some point usually well removed from the operator, which act to heat the turret and the forms thereon and the paper receptacles on the forms, but so 75 far as this feature of my invention is concerned other heating-means may be employed.

I claim:—

1. In a machine for forming paper receptacles, a turret, a plurality of forms arranged on said turret, pressure devices for coöperation with the forms, angle members movably connected with the pressure devices and pivotally supported on the turret, 85 a trip-member to which the angle members are successively presented in the rotation of the turret, and a downwardly inclined yielding finger carried by and projecting beyond each angle member to ride beneath and be 90 engaged by said trip member, whereby to operate each angle member on its pivotal connection in the movement of such angle member past the trip member.

2. In a machine for forming paper receptacles, the combination of a turret, a plurality of forms arranged on said turret on which the bodies and bottom-pieces are placed, inverted cups shaped to fit the forms which are arranged above the forms, pivoted 100 supporting-arms to which said cups are loosely connected, projections and springs on said supporting-arms for engagement with the cups, respectively at opposite sides of the center, and holding-springs connected 105 with said supporting-arms, substantially as described.

3. In a machine for forming paper receptacles, the combination of a turret, a plurality of forms arranged on said turret on 110 which the bodies and bottom-pieces are placed, pressure-devices for engagement with the bottom-pieces on the forms, movable supporting-means for said pressure-devices, holding-means connected with said 115 supporting-means and automatic means to lift said supporting-means to cause the pressure-devices to disengage the bottom-pieces, said automatic means operating in succession against and with said holding 120 means, substantially as described.

4. In a machine for forming paper receptacles, the combination of a turret, a plurality of forms arranged on said turret on 125 which the bodies and bottom-pieces are placed, pressure-devices, coextensive with the bottom-pieces and shaped to fit the forms which are arranged above the forms, supporting-means for said pressure-devices which are movable to permit movement of 130

the pressure-devices toward and from the forms, and holding-means connected with said supporting-means for holding the pressure-devices in engagement with the receptacles on the forms, and heating-means for the paper receptacles, into the zone of which they are successively brought, substantially as described.

5. A machine for forming paper receptacles including a form to receive the body of the receptacle, a pressure element shaped to fit the body and adapted to overlie and press upon the bottom piece of the receptacle, a fixed element and a yielding element 10 coöoperating with the pressure element during its engagement with the bottom piece.
6. A machine for forming paper recep-

tacles including a form to receive the body of the receptacle, a pressure element shaped to fit the body and adapted to overlie and 20 press upon the bottom piece of the receptacle, a supporting member to which the pressure element is pivotally connected, and means carried by said supporting member to cooperate with the pressure element to 25 center the same in the pressing operation.

In testimony whereof, I have signed my name to this specification, in the presence of two subscribing witnesses.
